UNITED STATES PATENT OFFICE.

JOHN WILLIAM ZELLERS, OF CHICAGO, ILLINOIS, ASSIGNOR TO GOODMAN MANUFACTURING COMPANY, OF CHICAGO, ILLINOIS, A CORPORATION OF ILLINOIS.

CUTTER CHAIN.

Application filed June 18, 1924. Serial No. 720,733.

This invention relates to improvements in cutter chains for mining machines and has for its principal object to provide a simply and durably constructed chain block.

6 The invention may be best understood by reference to the accompanying drawings, in which:—

Figure 1 is a side view of the chain block with the cutter bit in place therein;

10 Figure 2 is a perspective view of the chain block and the cutter bit;

15 Figure 3 is an end view of the chain showing it in position in the cutter head of a mining machine, the head being indicated in dotted lines; and

20 Figure 4 is a sectional view taken on line 4—4 of Figure 1.

25 In these drawings, which illustrate one form in which my invention may be embodied, a chain block 1 is adapted to be pivotally connected to another block by a series of straps 2, 2. The chain in use is an endless chain driven by a sprocket and working in a grooved cutter head 3 (see Figure 3). The blocks and straps are provided with restraining lips 5, 5 and 6, 6, to retain them in the guideways 7, 7 of the grooved cutter head. The blocks are provided with cutter bits 8, 8. The cutter chain is made up of a series of chain blocks extending at various angles to the grooved cutter head, as shown in Figure 3. For the purpose of illustrating my device I have shown in detail one of such chain blocks 30 having its cutter bit centrally located, that is to say, perpendicular to the grooved cutter head, but it will be understood that the same features of construction are used in the other chain blocks having varying degrees of inclination to said cutter head.

35 The bit 8 is preferably made of flat bar stock, the central portion 9 having a substantially uniform rectangular cross-section and with its opposite ends forming the cutting points 10, 10, inclined with the front or cutting face extending in an obtuse angle with respect to the adjacent front face of the central portion 9. The shape of the extreme ends of the cutter bit may be varied, depending upon the working conditions to which they are put. In the form shown a pick point is provided.

40 In order to secure a bit of the shape shown and described the cutter block is provided with a bit-receiving aperture 11 hav-

ing an opening 12 of rectangular shape providing a working groove for the bit when held in place as shown in Figure 1. The lower portion of the aperture however is widened in longitudinal section so as to 45 accommodate the lower inclined portion of the bit. In the form shown the bit-receiving aperture is provided with a front wall 13 which may be substantially at a right angle to the longitudinal axis of the bit and a rear wall 14 which is inclined slightly rearwardly and inwardly from the outer face of the bit so as to provide an inclined bearing surface for the rear face of the bit. The front wall 13 and the rear wall 14 therefore diverge inwardly to provide suitable enlargement for the forwardly inclined cutting portion 10, as clearly shown in dotted lines in Figure 1. The bit is secured in place by means of a set screw 16 extending through the front face of the bit block preferably inclined substantially at right angles to the bearing surface 14 against which the cutter bit is engaged. The bottom of the aperture may be provided with a communicating passage 17 which may be desirable for supporting the bit aperture core in cases where the block is cast.

50 The block and bit construction as above described affords a simple and durable device in which the cutter bit having double cutting ends and especially these cutting ends inclined forwardly in the main body of the bit may be securely clamped in place in the block. The bit is maintained in engagement with a solid bearing surface along the rear face which is particularly desirable in cutter chains of this character, and said bit projects from the cutter block at a forwardly inclined angle.

55 Although I have illustrated and described one form in which my invention may be embodied, it will be understood that the construction and arrangement of the various parts may be altered without departing from the spirit and scope of the invention. Furthermore, I do not wish to be understood as limiting myself to the particular construction shown, excepting as it may be defined in the appended claims.

60 I claim as my invention:

65 1. A chain block for mining machines having a bit provided with a central portion substantially uniform in cross-section and provided with offset cutting portions at

- opposite ends thereof, said chain block being provided with a bit-receiving aperture having its outer margins adapted to conform substantially with the cross-section 5 area of said centre portion of the bit and having its inner portion enlarged in cross-section to receive the offset portion of the bit, and means for securing said cutter bit in said aperture.
- 10 2. A chain block for mining machines having a bit provided with a central portion substantially uniform in cross-section and provided with offset cutting portions at opposite ends thereof, said chain block being 15 provided with a bit-receiving aperture the front and rear walls whereof diverge inwardly, and means for securing said cutter bit in said aperture.
3. A chain block for mining machines 20 having a bit provided with a central portion substantially uniform in cross-section and provided with offset cutting portions at opposite ends thereof, said chain block being provided with a bit-receiving aperture having 25 a substantially perpendicular front wall and an inwardly and rearwardly inclining rear wall, and means for securing said cutter bit in said aperture.
4. A chain block for mining machines having a bit provided with a central portion substantially uniform in cross-section and provided with offset cutting portions at opposite ends thereof, said chain block being provided with a bit-receiving aperture the front and rear walls whereof diverge inwardly, and a set screw at right angles to the centre portion of said cutter bit for securing the latter in said aperture. 30
5. A chain block for mining machines having a bit provided with a central portion substantially uniform in cross-section and provided with offset cutting portions at opposite ends thereof, said chain block being provided with a bit-receiving aperture, the forward wall whereof is substantially at right angles with the upper margin 40 of the block and the rearward wall diverging rearwardly and inwardly, and a set screw for securing said cutter bit extending through said front wall and substantially at right angles with the rear wall of said aperture. 45

Signed at Chicago, county of Cook and State of Illinois, this 2nd day of June, A. D. 1924.

JOHN WM. ZELLERS.
